Primary Examiner — Llorellys Martinez*Assistant Examiner* — Kwabena A. Ankobiah*(74) Attorney, Agent, or Firm* — Georgi Korobanov**CLAIM**

The ornamental design for a smart watch, as shown and described.

DESCRIPTION

FIG. 1 is a front and top perspective view of a smart watch, showing my new design;

FIG. 2 is a rear and bottom perspective view thereof;

FIG. 3 is a rear view thereof;

FIG. 4 is a front view thereof;

FIG. 5 is a right side view thereof;

FIG. 6 is a left side view thereof;

FIG. 7 is an enlarged top plan view thereof;

FIG. 8 is an enlarged bottom plan view thereof;

FIG. 9 is an enlarged view of portion 9 shown in FIG. 1; and, FIG. 10 is an enlarged view of portion 10 shown in FIG. 2. The dash-dot-dash broken lines in FIGS. 1, 2, 9, and 10 are included to show a partially enlarged view only and form no part of the claimed design.
